ELASTIC OR RUBBER THREAD OR YARN
AND METHOD OF MANUFACTURING THE
SAME

Thomas Lewis Shepherd, London, England

Application March 18, 1935, Serial No. 11,720
In Great Britain March 21, 1934

6 Claims. (Cl. 117—2)

This invention relates to elastic or rubber threads or yarns which are intended to be subsequently used in the manufacture of fabric, clothing, lacework and the like or parts thereof or for wearing apparel of any description.

Such a yarn is usually made by first forming a core of a rubber filament or thread which has been either extruded into a coagulating or spinning bath, or has been cut from a sheet of rubber, and such filament is then covered with a double helical winding of cotton, silk and the like of relatively opposite twist so as to form as it were a fibrous jacket or covering to the rubber core. This fibrous covering will constitute a protection to the core when the threads or yarns are laid across one another as will result when the yarn is being woven or knitted into a fabric, so that the intercrossing cores will not cut into one another.

Such a fabric covering is not altogether successful in practice, because the twisted convolutions of the fibrous covering may and do exert an undesired influence on the degree of stretch to be given to the elastic yarn, and interfere with its contractibility back to normal size. The application of the fibrous covering is expensive and requires to be very carefully executed, and again the fibrous covering possesses a tendency to creep or move relatively to the core.

Moreover, when rubber threads are to be led into a loom or knitting machine so as to be formed into a fabric, it is very often difficult to control the rubber threads because of the extensive and variable stretch that they possess and the result of this capacity of the thread results in the fabric when completed having a non-uniform surface appearance or causes shirring and other defects in the finished material.

The object of the invention hereinafter described is to overcome this last mentioned defect and also to prevent the threads cutting into one another when they are laid across one another or across textile threads as is the case when they are woven into a fabric.

Other objects and advantages will appear from the following description.

I find that by using comminuted material according to the invention, a thread may be produced which is resistant to cross-cutting, does not possess a frictional surface, possesses reduced extensibility, and may be dyed.

The invention will now be described by way of example with reference to the accompanying drawing in which—

Figure 1 is a diagrammatic view of a device

whereby a rubber thread may be coated as will hereafter be described;

Figure 2 is a view of two coated threads being twisted together;

Figure 3 is a diagrammatic view of apparatus for extruding a thread.

The rubber thread is to be coated with comminuted material and a suitable adhesive is prepared, so that the comminuted material is held in suspension. The thread *b* to be covered is now drawn or otherwise passed under rollers *e* and through the mixture *d* in a bath *c* in the manner shown in Figure 1 so that it will pick up a coating of the mixture, i. e. the solution and the comminuted material. When the thus coated thread leaves the receptacle, it is subjected to a squeezing or pressing action by the rollers *f* to consolidate the coating and bring it into intimate contact with the thread. The coated thread is then led away for drying, after which a vulcanizing or a hardening treatment may be employed.

Such a system of coating thread may be extended to the manufacture of compound threads or yarn according to which and referring to Figure 5, two (or more) threads of rubber *m* in an unvulcanized or tacky condition are brought together and twisted or doubled one upon the other. These threads which have already been coated as shown at *n* with the finely divided or comminuted material or have had such material incorporated therein and under tension or not are then twisted together as shown at *o* by any suitable means (not shown) and while this twisting proceeds the finely divided material already present on each thread becomes firmly amalgamated and mixed with the doubled thread *o* which can now be described as yarn, and it will be understood that an additional quantity of the coating mixture as indicated at *p* may be added as the manufacture of the compound thread proceeds.

The rubber thread to be used according to any of the above arrangements may be produced in various ways, for instance it may be formed by extruding or otherwise or it may be a thread already vulcanized.

Additional comminuted material may also be mixed in suspension in the bath containing the rubber solution and the mixture extruded through nozzles as usual into a coagulating bath, which system will be hereafter referred to in connection with Figure 3, the resulting rubber thread being then coated as described above.

The adhesive when used may be any kind

which is suitable and may comprise rubber, Celuloid, cellulose, a suitable varnish, a resin, synthetic or natural, glue, linseed oil and the like.

Further, it may have a consistency which sets or is stabilized by means of heat, chemical action or otherwise so that it may be left in any desired final condition, that is to say it will be flexible or tough or hard. Moreover, the adhesive may be vulcanizable similarly to rubber and 10 the term "rubber" used herein should be understood as including rubber in any suitable form, namely any of those compounds as used for proofing cloth and the like material, any aqueous dispersion thereof, latex or a natural 15 or artificial compound of rubber and in a concentrated or compounded form.

It is to be noted that substances may be used according to the invention that are usually treated as waste. Moreover the subdivided material 20 may be dyed or capable of absorbing a dye so as to impart to the finished product a multi-coloured or speckled appearance and in some cases the coated filament after vulcanization or hardening may be so treated with a solvent that small 25 portions of the outer skin of the coating will be removed or dissolved so as to expose to view the finely subdivided material and thus give the thread a speckled appearance.

Referring to Figure 3, *q* shows a bath containing a mixture of an aqueous dispersion of 30 latex, for example, suspended in which is a desired quantity of finely divided comminuted flock-like or similar material indicated at *r*. From the bath *q* the solution is pumped at *s* into 35 a duct *t* leading to any usual form of extruding nozzle *u*, the duct and the nozzle being submerged in a tank *v* containing any suitable liquid coagulant such as *w*. The compound thread which is extruded by the nozzle *u* will thus be

coagulated in passing through the coagulating liquid *w*, the thread being subsequently led away under a suitable tension if desired over a roller *x* for subsequent treatment including the coating as described above.

I claim:

1. A compound thread formed of elastic rubber and coated with a protective material to hold the thread rigid, such protective material being lacking at predetermined local areas to form a 10 speckled thread.

2. A compound rubber thread consisting of rubber threads twisted together and holding additional comminuted material in the interstices, each rubber thread being provided with a coating 15 throughout which comminuted material is suspended.

3. A process for coating rubber thread with a 20 coating throughout which comminuted material is suspended which consists in passing it through a bath of liquid coating throughout which comminuted material is suspended, consolidating the coating on the thread by rollers, and drying the liquid on the thread.

4. A process for forming a compound rubber 25 thread, which consists in coating rubber threads as specified in claim 3, with the addition that the threads are twisted together before drying.

5. A process for forming a compound rubber 30 thread, which consists in coating rubber threads as specified in claim 3, with the addition that the threads are twisted together before drying, and that comminuted material is added during the twisting.

6. A process as claimed in claim 3, and removing the outer skin of the coating at least in 35 parts.

THOMAS LEWIS SHEPHERD.
